AUTOMATIC DRILLING CONTROL

Joshua C. Conrad and Harold L. Conrad,
Oklahoma City, Okla.

Application November 3, 1941, Serial No. 417,638

3 Claims. (Cl. 188—110)

This invention relates to well drilling equipment and it has particular reference to apparatus for controlling the braking equipment of the drilling drum of a rotary rig.

The principal object of the invention is to provide automatic means responsive to the weight of a load on the drilling lines to correspondingly control the friction brake of the drilling drum to thereby maintain control of the tools in the well. For example, when the weight on the drill bit increases in the course of drilling, this factor is instrumental in so actuating the invention as to effect automatic depression of the brake lever of the drilling drum, to stop the same and cease feeding out line. Conversely, when the bit drills down to decrease the load thereon, the invention is effective to release the brake of the drilling drum to feed out drilling line and thereby increase the load on the bit. In this manner, uniform and constant weight is imposed on the bit with a minimum of attention.

Another object of the invention is to provide, through the medium of the invention, a safety factor, in that should the string of pipe separate in the well, the sudden lessening of weight supported by the dead line will instantly operate the invention to set the brake on the drilling drum and hold the remainder of the pipe supported by the drilling line.

Another object of the invention is to provide in conjunction with the automatic drilling control, visible means for indicating the weight of the load on the drilling line at all times and by which the driller is enabled to determine the performance of the automatic control.

Yet another object of the invention is to provide means for maintaining true adjustment in the line connecting the automatic control with the drilling drum brake lever to insure simultaneous operation of these elements under any and all conditions.

With the foregoing objects as paramount, the invention has further reference to certain features of accomplishment, to become manifest as the description proceeds, taken in connection with the accompanying drawings, wherein:

Figure 1 is an elevational view of a rotary well drilling rig, with the invention shown thereon.

Figure 2 is an elevational view of an apparatus embodying the invention.

Figure 3 is a view on line 3—3 on Figure 2.

Figure 4 is a view on line 4—4 on Figure 2.

Figure 5 is a modified form of apparatus serving in the capacity of that shown in Figure 2.

Figure 6 is a detail view of a device for retain-

ing the brake line when the drilling control apparatus is not in use.

Figure 7 is another modified form of the invention.

Figure 8 is a front elevational view of the device shown in Figure 7.

Figure 9 is yet another modification of the structure shown in Figures 2 and 7, and

Figure 10 is a plan view of the device shown in Figure 9.

Continuing with a more detailed description of the drawings, reference is primarily made to Figure 1 wherein is shown a derrick 10 of conventional construction, as well as a rotary table 11 and draw works 12. The usual drilling drum 13 is shown in connection with the draw works, having a brake drum 14 and a brake operating lever 15. Conventional also is the swivel 16, kelly 17, traveling block 18, crown block 19, dead line 20 and drilling line 21 which latter is threaded, in the usual manner over the crown block 19, through the traveling block 18, thence over the crown block from which it extends downward to the drum 13 and wound thereupon.

In drilling, the driller attends the drum 13, feeding out the line 21 as the bit descends and manipulating the drum by means of the lever 15. This operation has been heretofore accomplished manually and requires the undivided attention of a highly skilled operator at all times, whose work depends largely upon experience, enabling him to "feel" the action of the drum, in the absence of visible means and automatic equipment to aid in the operation of the drilling drum and its effect upon the line.

The invention lessens materially the responsibilities of the driller and at the same time reduces his labor, yet improving upon the accuracy of his efforts by providing automatic means for controlling the movements of the drilling drum.

Accordingly, the invention consists of a frame 22 (Figs. 2, 3 and 4), to one end of which is rigidly connected an obtuse angular arm 23. This arm is constructed so that one plane thereof is attachable, by means of U-bolt 24 to the dead line 20, the meeting point *a* (Fig. 2) of the planes of the arm determining one bend in the cable 20 while the point of connection of the latter to the arm by the U-bolt, determines another bend therein. The object is to provide three bends in the dead line and to utilize the force tending to straighten the line for useful work, which, in the present case, is to compress the coiled spring 25, disposed in the frame 22, for the purposes to be hereinafter set forth.

Extending axially through the frame 22 and spring 25 is a rod 26. The spring 25 is interposed between a plate 27, affixed in the frame near one end thereof and a collar 28 mounted on the rod. The collar 28 is held against movement by nut 29 but is adjustable to vary the tension on the spring 25.

The opposite end of the rod 26 carries a yoke 30, in which is mounted a grooved roller 31, against which the line 20 is passed. It is apparent therefore that any tensile strain imposed on the line 20 will have a tendency to straighten the latter and the force thus created will cause the rod 26 to move axially toward the cable, compressing the spring 25.

Mounted on and extending at right angles to the rod 26 is an arm 32, reinforced by webs 33 and held in adjustable position on the rod 26 by nuts 34, threaded on the rod. On the opposite end of the frame 22 are mounted bearings 35, spaced apart. A shaft 36 is journaled in these bearings and has a sprocket wheel 37 mounted thereon midway between its ends. A sheave 38 is mounted on one end of the shaft outside of the frame 22. A sprocket chain 39 has one end secured to the arm 32 and is passed over the sprocket wheel 37 to embrace a portion of its toothed periphery and is secured thereto at b (Fig. 2).

Lying in the groove of the sheave 38 and surrounding a part of its periphery is a line 40, one end of which is affixed to the periphery of the sheave at c. This line which will be herein-after referred to as the "brake line," for clarity, extends downward from the position of the apparatus on the dead line 20, through the derrick floor, under a sheave 41, across underneath the floor; under another sheave 42, upward through the derrick floor and is attached, as shown in Figure 1, to the handle of the brake lever 15. A device 43 provides the actual connection between the brake line and lever 15 and, through the medium of a threaded rod 44 and crank 45 a means for adjusting the tension on this line is effected.

It will be understood that the showing in Figure 1 is more or less diagrammatic for better comprehension and that the invention may be located in positions best suited for the conditions under which it operates.

In operation, the machine is clamped to the dead line 20 in the manner shown, and the brake line threaded under sheaves 41 and 42 and connected to the brake lever 15. The crank 45 is rotated to impose just the right amount of tension on the brake line 40 and with other factors in proper relative adjustment, drilling is started.

Presuming that the maximum load is 100,000 pounds and the driller desires to impose 10,000 pounds on the drill bit. The temper screw or tension adjuster 44 is manipulated to allow for the difference between the actual weight of the full load and that assumed by the bit. The tensiometer 46 (Figure 1) mounted on the dead line 20 above the automatic control, will show 90,000 pounds, indicating to the driller that 10,000 pounds of weight rests on the bit. The invention, being adjusted to requirements, will allow the drilling drum 13 to operate until the bit has reached such depth as to decrease the load thereon. As the bit progresses, the tension on the dead line, which carries the load, increases causing the rod 26 to move axially to compress the spring 25. This action results in a slackening of the brake line 40, allowing the brake lever 15

to rise, due to spring 5, relieving the friction on the brake drum 14 and slackening off on the drilling line 21. However, this action is only momentary and the brake line 40 is again placed under tension as soon as the drill bit again assumes the allotted weight of the load, which results in a slackening of the dead line 20. Obviously, this slackening of the deadline will relieve tension on the spring 25 and allow it to expand, causing the arm 32 to move away from the dead line, unwinding the chain 39 on the sprocket 37, rotating the latter counter-clockwise, to similarly rotate the sheave 38. The brake line 40 is therefore wound on the sheave taking up slack therein and urging the brake lever 15 downward to thereby set the brake and prevent further unwinding of drilling line. This action is repeated as drilling proceeds and the weight variations are indicated on the dial of the tensiometer 46, of the type described in U. S. Letters Patent No. 2,092,303.

It is apparent also from the foregoing that should the string of pipe in the well break in two for any reason, the invention will operate to set the brake on the drilling drum. This is effected by the sudden lessening of weight on the dead line, allowing the spring 25 to expand, taking up slack in the brake line 40, thereby forcing the brake lever downward to operate the brake. This would also be true in any case causing undue slackening of the load suspending lines.

Figure 5 shows a slightly modified form of the structure just described. The principle of the device and the results achieved are identical but the general structure differs in that a bell crank 20a responds to variations in the degree of tension on the dead line to vary the tension on the brake line.

In this structure, the frame 21a carries the coiled spring 22a through which extends the strain rod 23a, the latter being provided with a yoke and roller 24a to engage the dead line 25a. As in the earlier described device, the obtuse-angular member 26a, by reason of its three points of engagement with the cable, places the required deflection in the same to compress spring 22a in accordance with the degree of tension imposed on the cable.

One arm of the bell crank 20a is connected, by means of a flexible line 27a to an arm 28a, secured to and extending outward from the strain rod 23a. The opposite arm of the bell crank is joined to one end of the brake line 29a, the latter extending downward under sheaves 30a and upward through the floor of the derrick. Obviously, when the dead line 25a is subjected to tensile stress, the spring 22a is compressed, causing bell crank 20a to move on its pivot in a clock-wise direction. Accordingly, the brake line 29a is slackened but the slack is taken up by upward movement of the brake lever 15 which is caused to so move by spring 5, (Fig. 1). When tension on the dead line 25a is relieved, spring 22a expands, rotating the bell crank 20a in the opposite direction, tensioning brake line 29a and setting brake lever 15.

Figure 6 illustrates a tensioning device for the brake line which may be substituted for that shown in Figure 1 and the brake line, for the sake of clarity, is identified by the same character of reference 29a, employed to denote the brake line in Figure 5, just described. This tensioning device also serves to retain the brake line during periods when not in use. The device consists of a pipe 31a, slotted on one side to receive

a roller 32a as a guide for the line 29a, passing upward through the pipe 31a. A collar 33a rests on the upper end of the pipe and is received by the lower end of a spring 34a. Another collar 35a rests on the upper end of the spring 34a and is concaved to receive the rounded end of the lower portion of a frame 36a which latter receives the handle of lever 15. A screw rod 31a, manipulated by crank 38a holds the frame in position on lever 15a and also may be manipulated to vary the tension on line 29a. When not in use, the device, by reason of a hinge 39a, connecting pipe 31a to the derrick floor is released from the brake lever 15 and moved to a horizontal position on the floor below the lever 15.

In Figures 7 and 8 a further modified form of the invention is shown. This modified form consists of a closed housing 47 which, in the present case, is square in transverse section and extending axially through this housing is a shaft or rod 48. Connected by bolts 49 to the lower end of the housing 47 is a small, closed cylinder 50 into which the lower end of rod 48 extends and carries a piston head 51 thereon, ground to conform closely to the walls of the cylinder 50. This cylinder contains a quantity of oil and the resistance thereof to movements of the piston head and consequently the rod 48, affords a means to absorb shocks resulting from sudden jerks imposed on the cable.

Surrounding the rod 48, interiorly of the housing 47 is a coiled spring 52 having considerable compressive resistance. One end of the spring bears against a flanged collar 53 at the top while the lower end of the spring bears against a similar flanged collar 54, the latter being secured adjustably on the rod by means of nuts 55. These nuts are likewise employed to hold one end of an arm 56 which extends outwardly at right angles from the rod 48, through a slot 57 in the housing and to which reference will again be made presently.

Also carried by the rod 48 is a guide member 58, shaped to conform to the walls of the housing 47. This member is ground to a close fit in the housing and augments the shock absorbing action of the piston head 51 in the small cylinder therebelow.

Mounted on top of the housing 47 is a bracket bearing 59. Journaled in this bearing is a pin 60, providing a fulcrum for an angular member 61. This member, as apparent in Figure 7 is comprised of a plate bent on a line midway between and transverse to its longitudinal axis to provide two portions on different planes. One plane thereof has an aperture to receive the upper end of the rod 48 which latter carries a half-round nut 62, against which bears lock nuts 63. The aperture is countersunk to conformably receive the half-round nut 62 since the member 61 is movable on its fulcrum 60 for the purpose to be later explained. The other plane of the member 61 has pairs of holes 64 therein to selectively receive a U-bolt 65.

The U-bolt 65 embraces the cable or dead line 66, which passes downward axially along the housing 47, under a grooved roller 67, mounted on the housing near its lower end. In passing over the fulcrum point of member 61, a bend is placed in the cable and it is through the offices of the three points of engagement with the cable that the invention is operated to obtain the result expected.

Variations in the weight of loads carried by the cable correspondingly vary the degree of bend

in the cable opposite the fulcrum point 60 of the member 61. These variations influence the member 61 to rock on its fulcrum and in so doing, the spring 52 is either compressed or expanded by movements of the rod 48.

Connected to the outer end of the arm 56 is a sprocket chain 68 which latter extends over a part of the periphery of a sprocket wheel 69. The sprocket wheel 69 is mounted on a stub shaft 70 which also carries an annularly grooved sheave 71.

It is apparent that when a load is imposed on the cable 66 sufficient to overcome the resistance of spring 52, the member 61 will move in a counter-clockwise direction on its fulcrum, urging the rod 48 upward and compressing spring 52. Simultaneously, the arm 56 is moved in the slot 57, allowing the chain 68 to wind on the sprocket wheel 69.

Wound on the sheave 71 is a line 72. This line extends downward under a sheave 73 thence under a similar sheave 74 and upward to a point of connection to a tensioning member 75 which latter, in turn, is connected to the handle of the brake lever 76, shown fragmentarily in Figure 7. Reference to the tensioning member will again be made presently.

It will be understood that the brake lever 76 is held in inoperative position by means of a spring such as S in Figure 1, since the brake mechanism is of conventional and well known construction. This being true, the normal movement of the brake lever, under the influence of its spring action, exerts a pull on the line 72, which will, as in the previous case, be referred to as the brake line. This pull will take up slack in the brake line caused by the winding of the chain 68 on the sprocket wheel, as explained.

Therefore, it will be seen that as the line 66 which supports the full load of equipment is placed under tension, the resulting action will be the releasing of the brake on the drilling drum (not shown) to allow the same to feed out more line. Conversely, when the line 66 is relieved of a part of its load, the member 61 moves in a clockwise direction under the expanding influence of spring 52, which action moves the rod 48 and consequently the arm 56 downwardly to unwind the chain 68 from sprocket wheel 69. This action places the brake line 72 under tension and consequently forces the brake lever 76 downward to apply the brake and thereby stop the drilling drum.

The tensioning device for the brake line 72 is shown in Figure 8 and is identical to its counterpart shown in Figure 6. It consists of a frame 77 which is received by the handle of the brake lever 76. A pipe 78 is hinged at 79 to the derrick floor and is slotted to receive a roller 77a against which the line 72 rests in operation. A collar 78a is disposed in the end of the pipe 78 and a coiled spring 79a rests on this collar. A second collar 79b is disposed in the upper end of spring 79a and has a concave end to receive the convex lower end of the frame 77 to produce the effect of a ball and socket to allow freedom of movement of the frame so that it may adjust itself to the movements of the brake lever 76. A screw rod 80, manipulated by a crank 80a holds the tensioning device on the brake lever and by rotating this screw, tension on the line 72 is increased or diminished.

Moreover, when the tensioning device is not in use, such as in "making trips" to change bits or for other purposes, the frame 77 is removed

from the brake lever and by virtue of the hinged pipe 78, the entire assembly may be moved to a horizontal position on the derrick floor, under the brake lever, out of the way, yet maintaining, through spring 79a, moderate tension on the brake line 72.

In Figures 9 and 10 is shown a still further modification of that part of the invention which is attached to the dead line, which latter in this case is indicated by reference character 81.

The frame of the machine is comprised of a plate 82 having laterally directed portions 83 forming bearings for a rod 84 extending the length of the plate 82, in parallel relation thereto. Surrounding the rod and held between one portion 83 of the plate and an arm 85 on the rod 84 is a coiled spring 86. A yoke 87 is mounted on the forward end of the rod 84 and carries a grooved sheave 88. The line 81 lies in the groove of a companion sheave 89, journaled in bearings 90 on the frame and continues downward behind the sheave 88, thence outward over another sheave 91. It is apparent therefore that when the line 81 is placed under tension, the rod 84 will be forced to the left in Figure 9, compressing the spring 86.

Connected to the arm 85 is a sprocket chain 92 which overrides a part of the sprocket wheel 93, mounted on a stub shaft 94. Mounted also on this shaft is an annularly grooved wheel 95, on which is wound a line 96 comparable to the brake lines referred to in the earlier description of the other forms of the invention.

When the spring 86 is compressed as explained, the chain 92 will wind on the sprocket wheel 93, while the line 96 is fed off the sheave 95, the results obtained being identical to those obtained by the previously described devices.

Manifestly, the construction as shown and described is capable of some modification and such modifications as may be construed to fall within the scope and meaning of the appended claims is also considered to be within the spirit and intent of the invention.

What is claimed is:

1. An automatic control for a friction brake comprising a load carrying line, a frame having an angular arm mounted upon said line for producing a deflection therein variable in relation to the variations in the weight of the load on said line, a spring held normally under compression by the tensile stress imposed on said line, a strain

rod extending axially through said spring and actuated by said load line, a stub shaft mounted on and extending at right angles to said frame, a sprocket wheel on said shaft, a chain fastened at one end to and embracing a portion of said wheel with its opposite end connected to said strain rod whereby to be actuated in accordance with variations of the load carried by said line, a sheave arranged for common rotation with said sprocket wheel and a line connected at one end to said sheave and at its opposite end to the operating lever of said friction brake to control the movements thereof in relation to the variations in load carried by said load line.

15 2. An automatic control for friction brakes comprising a load supporting line, a frame having a rigid angular arm to which said line is secured at two points, a rod axially slidable in said frame under spring tension and connected to said load supporting line to produce a bend therein to effect its movement in direct relation to variations in tension on said load supporting line, a stub shaft affixed to and extending from the side of said frame, a sprocket wheel freely mounted on said shaft, a chain having one end fixed to said sprocket wheel to partially surround the same, with its opposite end secured to said rod, a sheave also mounted on said shaft for rotation by and with said sprocket, a line connected at one to and 20 partially surrounding said sheave and having its opposite end connected to the lever of said brake whereby to effect movement of said lever in relation to variations in the load carried by said load supporting line.

25 3. In an apparatus for automatically controlling the lever of a friction brake, a load supporting line, a frame mounted on said line, a rod mounted axially in said frame and connected to said line, a spring embracing and holding said rod under tension to produce a deflection in said load supporting line, a sprocket wheel mounted on the side of said frame, a chain connected at one end to and partially surrounding said sprocket wheel, with its opposite end fixed for movement 30 by and with said rod as changes in tension on said load supporting line occur, a sheave mounted for rotation with said sprocket wheel and a line connecting said sprocket and said brake lever to effect movement thereof in accordance with variations in tension on said load supporting line.
